UNITED STATES PATENT OFFICE.

PAUL G. ROESTI, OF MILWAUKEE, WISCONSIN.

ELASTIC-FLUID TURBINE.

No. 861,902.

Specification of Letters Patent.

Patented July 30, 1907.

Application filed December 24, 1906. Serial No. 349,286.

To all whom it may concern:

Be it known that I, PAUL G. ROESTI, a citizen of the Republic of Switzerland, residing at Milwaukee, in the county of Milwaukee and State of Wisconsin, have invented certain new and useful Improvements in Elastic-Fluid Turbines, of which the following is a specification, reference being had to the accompanying drawing, forming a part thereof.

This invention relates more particularly to means for assembling and holding the vanes in place.

The main objects of the invention are to facilitate assembling and securing the vanes of elastic fluid turbines exactly in their proper positions, and generally to improve the construction and operation of devices of this class.

It consists in certain novel features of construction and in the peculiar arrangement and combination of parts as hereinafter particularly described and pointed out in the claims.

20 In the accompanying drawing, illustrating the embodiment of the invention in various forms, like characters designate the same parts in the several figures.

Figure 1 is a plan view of a section of a perforated vane spacing band forming a part of the vane fastening; Fig. 2 is a section on the line 2 2, Figs. 1 and 3; Fig. 3 is a radial cross section on the line 3 3, Fig. 2; Fig. 4 is a section on the line 4 4, Figs. 2 and 6; Fig. 5 is a section on the line 5 5, Fig. 4; Fig. 6 is a side elevation and section on the line 6 6, Figs. 4 and 7, showing a number of assembled vanes with a portion of the finished vane supporting ring and a part of the rotating member of a turbine, the front clamping ring or piece being removed; Fig. 7 is a cross section on the line 7 7, Fig. 6; Fig. 8 is a plan view of a piece of a vane spacing band of a modified form for 35 solid vanes; Fig. 9 is a side elevation and section on the line 9 9, Figs. 8 and 10, showing a number of assembled vanes and a portion of a partially formed vane supporting ring; Fig. 10 is a cross section on the line 10 10, Fig. 9; Fig. 11 is a section on the line 11 11, Figs. 9 and 13; Fig. 12 is a section similar to that of Fig. 10 showing 40 a modification; Fig. 13 is a side elevation and section on the line 13 13, Figs. 11 and 14, showing a number of assembled vanes with a part of a finished vane supporting ring and a part of the rotary member of a turbine on which said ring is mounted; and Fig. 14 is a cross section on the line 14 14, Fig. 13.

Referring to Figs. 1 to 7 inclusive, *a* designates a perforated vane spacing and supporting band which may be made of steel or other suitable metal. The holes in this band are formed and spaced to correspond with the vane shanks and the desired spacing and position of the vanes. To provide a more extended bearing for the vane shanks and to hold them more firmly and exactly in place while the cast metal backing is being formed, 50 ears *b* may be left, as shown at the right in Fig. 1, and bent at right angles to the band, as shown in Fig. 2.

These ears serve also to prevent the detachment of the band *a* from the cast metal backing by centrifugal force or otherwise. Hollow vanes *c* which may be conveniently made from tubing or sheet metal, have their shanks primarily fitted to the holes in the band *a*. The shanks of the vanes are made somewhat narrower than the bodies of the vanes to form shoulders at *d*, as clearly indicated in Figs. 3 and 5, which accurately determine the extent to which the shanks may be inserted through the band *a*. After the vanes have been inserted in the band *a*, their shanks are spread, distorted or bent, as shown at the left in Fig. 2, and as indicated in Fig. 3 by the diverging dotted lines, or they are split and spread as indicated in Fig. 5, to prevent their withdrawal from the band. The band *a* is made in the form of a ring or in the form of segments of a ring.

When the vanes have all been assembled in the band *a* and their shanks have been spread or bent to hold them therein, they are placed with the band in a mold, 75 and molten brass, aluminium or other suitable metal is poured into the mold to form a backing or filling *e* around and between the vane shanks, next to the band. The vanes may be held firmly and exactly in the proper relation to each other while the backing or filling *e* is 80 being cast around and between their shanks, by brazing or soldering them to the band *a*, or by a jig clamp or other holding device which is afterwards removed. Only the shanks of the hollow vanes may be filled with the cast metal, as shown at the extreme left in Fig. 2, 85 or the vanes may be completely filled, as shown in connection with the second vane from the left in the same figure. After removing the casting with the vanes from the mold when it has the form shown in Figs. 3 and 5, it is turned or machined to the form shown in 90 Fig. 7, and formed in one or each side with a shoulder *f*, which intersects the edges of the vane shanks. It is now in readiness to be mounted upon or in the movable or stationary part of a turbine; and is clamped as shown in Fig. 7, between rings *g* and *h* formed with 95 grooves or recesses corresponding in shape with the finished backing or filling ring *e*.

Referring to Figs. 8 to 14 inclusive, showing the fastening means in connection with solid vanes, the metal band *a'* is formed with holes as shown in Fig. 8, 100 corresponding in shape with the cross section of the vane shanks and arranged and spaced to correspond with the desired spacing and position of the vanes. The shanks of the solid vanes *c'* are fitted and inserted as far as they will go into the band *a'*, the shanks being 105 reduced in width to form shoulders at their junction with the vanes for determining the extent of the insertion of the vanes through the band. After insertion into place in the band, the vane shanks are flattened, as indicated by cross hatching at the extreme right in Fig. 8, or they may be twisted, split and spread, as shown in Fig. 12, or otherwise distorted or bent to pro-

vent their withdrawal from the band while the backing or filling *e* is being cast around them. The backing or filling ring or segment *e* is then turned down or faced, and is formed with a shoulder on one or each side, 5 as before. One or more rows of vanes are then secured on the rotating member or in the casing of a turbine by clamping them between correspondingly grooved or recessed rings or parts. As shown in Figs. 13 and 14, the shouldered shanks of two sets of vanes with their 10 correspondingly shouldered cast metal backing or filling rings *e*, are clamped and held between correspondingly shaped rings *i*, fitted and mounted on the drum *j* of an axial flow turbine. The edges of the metal bands *a'* project on each side beyond the cast backing 15 or filling rings or segments *e* and are beveled to engage with correspondingly shaped and undercut grooves in the clamping rings *i*, as shown in Fig. 14, to resist centrifugal force and prevent detachment of the bands from their cast backing rings or segments.

20 As shown in Figs. 1, 4, 8 and 11, the holes in the retaining bands are punched or formed at such an angle as will secure the proper ratio between the inlet and exhaust openings of the passages between the vanes. For turbines of the impulse or action type, the vanes 25 may be of symmetrical form and set at such an angle as indicated by the line *x x*, Fig. 4, as will produce an increasing area in the passages between the vanes from the inlet to the exhaust.

Various changes in minor details of construction may 30 be made to adapt the fastenings herein shown and described to the movable and stationary members of turbines of various kinds, without departing from the principle and intended scope of the invention.

I claim:

35 1. In an elastic fluid turbine the combination of a metal band having holes formed and spaced to correspond with

the vane shanks and the desired spacing and position of the vanes, vanes having their shanks fitted and inserted in said holes and distorted to retain them in place therein and a backing of cast metal filling the spaces between the 40 vane shanks, substantially as described.

2. In an elastic fluid turbine the combination of a metal band having holes formed and spaced to correspond with the shanks and the desired spacing and position of the vanes, vanes having their shanks fitted and inserted in 45 said holes and distorted to retain them in place therein, and a backing of cast metal filling the spaces between the vanes and formed with a retaining shoulder intersecting the vane shanks, substantially as described.

3. In an elastic fluid turbine the combination of a metal band having holes formed and spaced to correspond with the vane shanks and the desired spacing and position of the vanes, vanes having their shanks fitted and inserted in 50 said holes and distorted to retain them in place therein, a cast metal backing filling the spaces between the vane 55 shanks and formed on the sides with retaining shoulders intersecting the edges of the vane shanks, substantially as described.

4. In an elastic fluid turbine the combination of a metal band having holes formed and spaced to correspond with the vane shanks and the desired spacing and position of the vanes, vanes having their shanks fitted and inserted in 60 said holes and distorted to retain them in place therein, a backing of cast metal faced on opposite sides and formed with a retaining shoulder intersecting the vane shanks, and rings or plates between which said backing with the vane shanks is clamped and held, substantially as described.

5. In an elastic fluid turbine the combination of a metal band having holes formed therein and spaced to correspond with the vane shanks and the desired spacing and position of the vanes, hollow vanes having their shanks fitted and inserted in said holes and a backing of cast metal filling the spaces between and the openings within the vane shanks, substantially as described.

In witness whereof I hereto affix my signature in presence of two witnesses.

PAUL G. ROESTI.
